HOIST CONTROL

Earl B. Lear, Garfield Heights, and John A. Hope, Lakewood, Ohio, assignors, by mesne assignments, to The Cleveland Pneumatic Tool Company, Cleveland, Ohio, a corporation of Ohio

Application May 4, 1942, Serial No. 441,646

2 Claims. (Cl. 254—187)

This invention relates to improvements in power hoists, and has reference particularly to hydraulic means for controlling the operation of the hoist, which means may be located at any convenient point either adjacent to or remote from the hoist itself.

One of the objects of the invention is the provision of hydraulic control means for operatively connecting a hoist drum to a drive shaft rapidly and without appreciable effort.

Another object is the provision of valve means embodying a single valve housing in which two valve plungers operate, either one of which is adapted to cut off circulation between a reservoir and the housing and to connect the inflow chamber of the housing with one only of a plurality of clutch operators.

A further object of the invention is the provision of novel valve means for the purpose stated.

Other objects and features of novelty will appear as we proceed with the description of that embodiment of the invention which, for the purposes of the present application, we have illustrated in the accompanying drawings, in which,

Fig. 1 is an elevational view of a power hoist embodying the invention.

Fig. 2 is an end view of the same looking in the direction of arrows 2—2 of Fig. 1.

Fig. 3 is a longitudinal sectional view on a larger scale taken substantially on the line 3—3 of Fig. 2, illustrating a reservoir and gear pump which may be employed in connection with the invention.

Figs. 4 and 5 are transverse sectional views taken substantially on the lines 4—4 and 5—5 of Fig. 3.

Fig. 6 is a detail sectional view taken substantially on the line 6—6 of Fig. 5.

Fig. 7 is a transverse sectional view on a larger scale, taken substantially on the line 7—7 of Fig. 1.

Figs. 8 and 9 are detail sectional views taken substantially on the lines 8—8 and 9—9 of Fig. 7.

Fig. 10 is a sectional view on a larger scale taken substantially on the line 10—10 of Fig. 1 showing the two control valves in neutral position.

Fig. 11 is a view similar to Fig. 10, but with one of the control valves in actuated position, and

Figs. 12, 13 and 14 are cross-sectional views taken substantially on the lines 12—12, 13—13 and 14—14 of Fig. 10.

In Fig. 1 of the drawings 20 indicates a pair of sledge runners or other supporting frame members upon which the different elements of a power hoist are mounted. As indicated herein these elements may comprise an electric motor 21, a flex-

ible or yielding drive 22, a gear box 23, a pair of drums 24 and 25, clutch means for each drum comprising clutch bands 26 and 27, and brakes for the individual drums comprising brake bands 28 and 29. The construction includes transverse frame members 30, 31 and 32 suitably attached to the sledge runners 20 and connected above the drums by a tie rod or brace 33. The parts thus far described are more or less conventional. 5 While two drums 24 and 25 are disclosed herein it will be obvious that in some aspects of the invention the number of drums may be varied, that is a single drum or more than two drums may be used. 10 In the frame members 30, 31 and 32 there is journaled a shaft 35, as by means of roller bearings one only of which is shown at 34 in Fig. 3. This shaft is driven by a motor 21 through reduction gearing, not shown, in gear box 23. 15 The clutch band 27 surrounds and is adapted to engage a cylindrical clutch surface on the periphery of a planetary gear carrier 36 that is rotatably mounted on shaft 35, as by means of roller bearings 37. A similar construction is provided 20 for the other hoist drum 24 and for any additional drums when used. When the carrier 36 is held against rotation by the contraction of band 27 drive is communicated from shaft 35 through a sun gear A keyed to the shaft and through 25 planetary gears B mounted on the carrier 36 through idler rollers C, the gears B in turn meshing with an internal gear D fixed with respect to the drum 25, this type of gear drive being well known in hoists. 30 Suitable means for contracting the clutch band 27 is shown in Fig. 7, where shoes 38 are riveted to the ends of the band and are fastened by bolts 39 or the like to shoe gripping arms 40 which have bifurcated ends through which are pins 41 35 that project through elongated slots 42 in ears that are integral with pistons 43. These pistons fit within cylinders 44 that are formed in blocks 45 which are fastened to the runners 20. Each of these pistons may be provided with suitable packing 46 held in place by rings 47 and headed screws 48. Motive fluid may be admitted to the cylinders 44 behind the piston heads through drilled passages 49. Normally the pistons 43 are forced away from each other by a compression 45 spring 50 which thereby functions additionally to expand clutch band 27. 50 The frame member 32, as indicated in Fig. 3, has a central opening large enough to receive an annular flange 51 made integral with a housing 52 which is hollowed out to form a reservoir 53

which may be filled with oil or other suitable liquid through an opening in its upper side normally closed by a screw plug 54. A port 55 connects the reservoir with a cylindrical valve socket 56, and a second port 57 connects this socket with a nipple 58 to which a discharge line 59 is connected. Housing 52 may be secured to frame member 32 by screws 60 or the like.

On the outer side of housing 52 there is mounted, as by means of screws 61, the housing 62 of a gear pump. This pump comprises a pair of intermeshing gears 63 and 64 which turn in a cavity of the housing shaped to fit their peripheries but providing intake and outlet spaces which communicate with passages 65 and 66 which lead to other passages 67 and 68 that extend to the valve socket 56, meeting that socket on opposite sides midway between the ports 55 and 57.

The hub of pump gear 63 has a dog clutch connection with a short shaft 69 mounted for rotation in a bushing 70 that is carried in housing 52. The opposite end of shaft 69 has a dog clutch connection with a plug 71 that is mounted in the end of hollow shaft 35 and is held against rotation with respect thereto by a pin 72. The gear pump is thereby coupled to drive shaft 35.

A cylindrical valve 73 is rotatably mounted in valve socket 56, which valve is cut away to form passages 74 and 75, and is provided with a stem 73' extending through a retaining plug 76 threaded into the outer end of the valve socket 56. To the valve stem may be attached a handle or the like by means of which the valve may be turned through an angle of 90°, its motion being limited to that amount by a pin and slot 77, 78 at its inner end. When this valve is in the position illustrated liquid from the reservoir flows through port 55, passages 74, 68 and 66 to the pump, through the pump, and then through passages 65, 67 and 75 to port 57. If, however, the direction of rotation of the pump gears should be changed, the valve 73 may be turned through an angle of 90° from the position illustrated, whereupon the flow of liquid from the valve socket 56 through the pump and back to that socket will be reversed.

In order to limit the pressure which may be set up by the pump in the discharge line 59 provide a by-pass between port 57 and reservoir 53 in which is mounted a valve that is adapted to yield when predetermined pressure is reached. This by-pass is marked 80 in the drawings. At an intermediate point of its length it is intercepted by a valve chamber 81 in which is mounted a cylindrical valve piece 82 which is urged toward its seat by a coil spring 83 that is backed by a screw 84 which may be turned one way or the other to adjust the force of the spring. A screw cap 85 serves to exclude dust and protect the valve.

The control for the liquid circulated by the pump is located at some point convenient to the operator, and comprises a valve housing 86 which in the present instance is mounted by means of bolts 87 upon a bracket 88 carried by the brace rod 33. This valve housing 86 has two cylindrical bores 89 and 90 which extend from top to bottom of the housing. An inflow chamber 91 and an outflow chamber 92 intercept both of these bores. There are also annular pockets 93 and 94 surrounding bore 89 between chambers 91 and 92 and similar pockets 95 and 96 surrounding bore 90. Pockets 93 and 96 are connected by a cross passage 97 and pockets 94 and 95 are connected by a similar cross passage 98. Below

the inflow chamber 91 there are two annular pockets 99 and 100 surrounding the bores 89 and 90 respectively.

Two plungers 101 and 102, which may be identical in form and size, are mounted to slide in bores 89 and 90. These plungers are urged upwardly by two coil springs 103 and 104 backed by screw plugs 105 and 106. The upward movement of the plungers is limited by nuts 107 and 108 as illustrated in Fig. 10. In plunger 101 there are constrictions 109 and 110. Constriction 109 serves to connect pocket 93 with chamber 92 when the plunger is in its normal or neutral position. Constriction 110 connects chamber 91 with pocket 94 when the plunger is in neutral and with pocket 99 when the plunger is depressed, as illustrated in Fig. 11. Similar constrictions 111 and 112 in plunger 102 function in like manner for connecting pocket 95 with chamber 92 and for connecting pocket 96 or pocket 100 with chamber 91. Drilled passages 113 and 114 extend upwardly from the lower ends of the plungers and connect with ports 115 and 116, respectively, the latter ports communicating with chamber 92 when the plungers are in their neutral or upper position.

Communicating with pockets 99 and 100 are two nipples 117 and 118 from which extend tubular conductors 119 and 120. Conductor 119 extends downwardly to the base of the machine and has branches which communicate with the passages 49 in the cylinder blocks 45 previously referred to. Conductor 120 extends down similarly and has branches which run along the base of the machine to a second set of cylinder blocks identical in form and function with the blocks 45, in which operate pistons similar to the pistons 43 for the actuation of clutch band 26.

In the valve housing 86 there is a nipple 121 communicating with inflow chamber 91 to which tubular conductor 59 is connected. Liquid from the delivery side of the pump therefore flows into chamber 91. Nipple 122 is mounted in the valve housing in communication with the outflow chamber 92, and with this nipple there is connected a tubular conductor 123 which extends downwardly to a nipple 124 mounted in the reservoir housing 52 near the top of the latter. Hence liquid received in chamber 92 may flow back to the reservoir through conductor 123.

The plungers 101 and 102 could of course be arranged to be depressed directly by the operator, but in order to reduce the necessary effort somewhat we prefer to provide a pair of levers 125 and 126 with knobs 127 and 128 on their ends, which levers are pivotally mounted in bifurcations in the upper ends of plungers 101 and 102, the fulcrums of the levers being supported by links 129 that are pivotally mounted upon ears attached to the housing 86, as shown in Fig. 1.

Operation.—Assuming that the motor 21 is running and that the shaft 35 is turning accordingly and the gear pump operating, and assuming that the control valves are in the neutral positions illustrated in Fig. 10, liquid will then be circulating from the reservoir through port 55, passages 74, 68 and 66 to the pump, and from the pump through passages 65, 67 and 75 to the conductor 59, whence it will flow to the inflow chamber 91 of the valve housing 86. From the chamber 91 it flows in parallel to the chamber 92, that is to say around restriction 109 into pocket 95, through cross passage 98 to pocket 95 and through restriction 111 to chamber 92, and also 75 around restriction 112 to pocket 96, through

cross passage 97 to pocket 93 and through restriction 109 to chamber 92. From chamber 92 it flows through conductor 123 back to reservoir. There is some tendency at the same time for liquid to flow from chamber 92 through ports 115 and 116 into the axial passages 113 and 114 of the plungers and out through tubular conductors 119 and 120 to the cylinders for operating the two clutch bands 26 and 27, but no pressure is built up in the cylinders because of the fact that free circulation at low pressure is permitted from the pump through the valves and back to the reservoir.

Now if it is desired to operate hoist drum 25 the operator depresses knob 127 and thereby moves plunger 101 downwardly against the action of spring 103 to the position illustrated in Fig. 11. This cuts off both paths of flow from chamber 91 to chamber 92, since constriction 109 no longer connects pocket 93 with chamber 92 and constriction 110 no longer connects pocket 94 with chamber 91. Both of the cross passages 97 and 98 are therefore blocked. Inflow chamber 91 is however connected with pocket 99 by constriction 110 and a flow of liquid is set up from pocket 99 through tubular conductor 119 to the passages 49 leading to the two cylinders 44. The pistons 43 then move toward each other against the action of spring 50 and the clutch band 27 is contracted upon the periphery of the planetary gear carrier 36, resulting in the rotation of drum 25. The passages 113 and 115 through the plunger are at this time cut off from the pocket 99, as will be apparent from an inspection of Fig. 11.

When it is desired to unwind the hoist the operator merely releases knob 127, whereupon plunger 101 returns to neutral position under the influence of its spring 103. When this occurs both cross passages 97 and 98 are again opened up and the normal low pressure circulation of the liquid resumes. At the same time pocket 99 is put into communication with the passages 113 and 115 through the plunger and the pressure previously built up in the line 119 is exhausted by way of the chamber 92 with the result that the spring 50 expands and forces the pistons 43 apart and into their cylinders, thereby expanding the clutch band 27 and leaving the carrier 36 free to rotate idly.

When the drum 24 is to be operated a similar procedure is followed except that plunger 102 is manipulated instead of plunger 101. The apparatus functions in the same way to stop low pressure circulation through both of the cross passages 97 and 98 and to open up pocket 100 to the inflow chamber 91, so that pressure fluid is transmitted through conductor 120 to the operating cylinders for clutch band 26.

In cases where it is more convenient to reverse 60

the position of the machine with respect to the work, making it necessary to reverse the direction of rotation of shaft 35, whereby the direction of rotation of the pump is also reversed, we can accommodate the present control to this change by merely shifting valve 73 from the position illustrated to a position at right angles to that illustrated. The connections for the pump will then be correct because the intake for the pump will then flow from port 55 through passage 75 to passage 67 and the discharge will flow through passages 68 and 74 to discharge port 57.

During actuation of a drum to perform a hoisting operation valve 82 remains closed until pressure has been built up sufficiently to cause clutch band 27 to firmly grip the periphery of planet gear carrier 36. Thereafter valve 82 opens sufficiently to let the discharge from the pump flow through the by-pass back to the reservoir 53, but not sufficiently to materially lessen the pressure in cylinders 44.

While we have shown herein two cross passages 97 and 98 in the valve housing 86 through which the flow of liquid in parallel from chamber 91 to chamber 92 is permitted, and while we prefer this arrangement when the hoist embodies two drums, it will be apparent that a single passage between these chambers would be within the spirit of the invention since either one of the passages 97 or 98 may be blocked by the depression of either one of the plungers 101 and 102.

Having thus described our invention, we claim:

1. In a power hoist, a frame, a drive shaft journaled therein, a drum rotatable around said shaft, means for rotating the drum from said shaft comprising a clutch, and hydraulic operating means for said clutch, said operating means comprising a gear pump supported by but separable from said frame endwise of said shaft, and a shaft extension in said pump aligned with and driven by said shaft but separable therefrom, one of the gears of said pump being carried by said shaft extension.

2. In a power hoist, a frame, a drive shaft journaled therein, a drum rotatable around said shaft, means for rotating the drum from said shaft comprising a clutch, and hydraulic operating means for said clutch, said operating means comprising a reservoir attached to but separable from said frame, and a gear pump attached to but separable from said reservoir, a shaft extension in said reservoir aligned with and driven by said shaft but separable therefrom, a shaft extension in said pump aligned with and driven by said first named shaft extension but separable therefrom, one of the gears of said pump being carried by said second shaft extension.

EARL B. LEAR.
JOHN A. HOPE.
